UNITED STATES PATENT OFFICE.

ROBERT C. TAFT, OF TOPEKA, KANSAS.

WALL-TIE.

SPECIFICATION forming part of Letters Patent No. 717,638, dated January 6, 1903.

Application filed February 25, 1902. Serial No. 95,631. (No model.)

To all whom it may concern:

Be it known that I, ROBERT C. TAFT, a citizen of the United States, residing at Topeka, in the county of Shawnee and State of Kansas, have invented new and useful Improvements in Wall-Ties, of which the following is a specification.

My invention pertains to that class of devices known as "wall-ties" and used in building construction for bonding or tying together the different sections of walls composed of brick, stone, or other similar material in which the units of the material are united by cement or mortar joints to form the aggregate mass of the wall; and the object of my invention is to supply means whereby various forms of walls and walls of various kinds of material may be bonded or have their vertical sections more securely tied together than has heretofore been possible by the usual methods of bonding. I attain this object by the use of flat strips or plates of any suitable metal, preferably galvanized iron or steel, such metals offering great strength, low cost, easy manipulation under the forming-dies, and by reason of the galvanizing satisfactory immunity from oxidation or rusting out. Other metals—such as copper, aluminium, &c.—may be used where the character of the work or the kind of material used require absolute permanence and security against any effect whatever from oxidation or decay.

The essential features of my invention consist in the novel forms given the metal strips to adapt them for use and secure the highest efficiency in accomplishing the desired objects, as will be hereinafter described, and which are illustrated by the accompanying drawings, in which—

Figure 1 is a top plan view and a longitudinal vertical plan view of one edge of a wall-tie formed according to my invention and adapted for use in bonding either solid or hollow walls composed of either brick or stone or other similar material the units of which are connected together by mortar or cement filled joints. Fig. 2 represents a top plan view with vertical edge view of my improved wall-tie, showing a modified form of the same, adapting it for use in bonding veneer walls,

by having a portion thereof bent up at right angle.

Like numerals refer to and indicate like parts or features of construction throughout the several views.

In Fig. 1 at or near the center of the strip forming the tie is provided the opening 1, which is so formed that the metal immediately surrounding the opening is given a "bur" projecting downward somewhat below the surface of under side of the strip. When the tie is used for bonding hollow walls, this opening serves as a "drip," through or from which moisture is precipitated. When used in solid walls, the projecting bur adds somewhat to the grip or resistance of the tie against moving. The reference-numeral 2 indicates the radially-arranged corrugations or ribs whereby the tie is given uneven surfaces which present resistance in different directions, and 11 indicates the burs, projecting in opposite directions from the flat plane of the strip, whereby additional resistance against pulling out of the strip is secured. These burs being formed by swaging up the metal around the openings present walls of resistance in all directions, and the mortar or cement passing through, filling, and hardening in said openings greatly strengthens the bonding force of the tie.

In the modified form shown in Fig. 2 the uneven surfaces formed by the radially-disposed ribs 2 and the burs 11, presenting walls of resistance in all directions, hold one end or portion of the tie firmly in mortar-joints 85 of the exterior section of the stone or brick veneer wall, while the other portion 12, being bent up at a right angle and provided with a suitable opening, allow it to be fastened by a nail or bolt to the interior section of wood or steel, thereby securely binding together the two sections of a veneer or composite wall. By this modification the tie becomes a complete device, adapted for use without extra labor of the workman in bending it down, which frequently forms an imperfect bedding in the mortar or disturbs the coherence of the mortar in its first action of "setting." These considerations—extra labor of the workman, imperfect embedding in the mortar, and dis-

turbance of the mortar, or especially quick-setting cement while in its first action of uniting with the brick or stone—are thought to be of such importance as to make this modification both useful and novel.

Having thus described the various novel forms devised to give efficiency to my invention and adapt it for use in accomplishing the proposed results, the reasons for such forms will be more clearly apparent by considering the requirements to be met in supplying a metal wall-tie.

In building construction where the walls are of brick or stone the best results are secured by bringing the individual blocks of material as closely in contact as possible, thus forming very thin joints between the units of the material to be filled by the mortar or cement which unites them into the solid mass. To meet this condition and adapt it for use in joints where the minimum of cement or mortar is used, while at the same time have it of such form that it may be used without regard to the size of the joint, my invention is formed of thin flat strips of metal in which corrugations and burs project from the surface in opposite directions, and these projections are so arranged that they offer resistance in all directions. Being bedded in the mortar or cement in the joint while it is in a plastic condition, when it "sets" or hardens the tie is firmly secured in place and extending across the vertical joints in solid walls or the dead-air space in hollow walls bonds or ties together all the parts of the wall more firmly, at less cost, and with less labor than were the bonding done by "chipping" and using brick or other material of which the wall is composed for bonding.

It may thus be seen that the essential features of my invention adapt it for use in walls of stone or brick alone or walls composed partly of brick and partly of stone, solid

walls or hollow walls, veneered walls, either with or without dead-air space between their exterior section of brick, stone, or terra-cotta and the wood or steel structure to which the veneering material is attached.

Having thus described my invention, what I claim as new, and desire to secure by Letters Patent of the United States, is—

1. A wall-tie composed of a strip of any suitable metal, and having uneven surfaces projecting in opposite directions from its flat sides, such projections being formed by corrugations or ribs, arranged radially, whereby they may offer resistance in different directions, substantially as and for the purposes shown and described.

2. A wall-tie composed of a strip of any suitable metal, and being provided with uneven surfaces, such uneven surfaces being produced by burs projecting in opposite directions from its flat sides, the openings around which such burs are formed, and the projections of the burs, offering walls of resistance in all directions, substantially as and for the purposes shown and described.

3. In a wall-tie composed of a strip of any suitable metal, and having uneven surfaces produced by radially-arranged corrugations or ribs, whereby it is held in the mortar-joint along one portion of its surface, the bending up of the other portion of the same at a right angle, 12, and providing an opening in said bent-up portion, whereby the tie is adapted to be secured to wood or steel inner structures of composite or veneer walls, substantially in the manner and for the purposes as shown and described.

In testimony whereof I affix my signature in presence of two witnesses.

ROBERT C. TAFT.
